RECORD REPRODUCING MACHINE

Edward J. Rabenda, Poughkeepsie, and Frank J. Furman, Endicott, N. Y., assignors to International Business Machines Corporation, New York, N. Y., a corporation of New York

Application March 2, 1945, Serial No. 580,668

12 Claims. (Cl. 164—115)

This invention relates to punching machines and more particularly to the type which enables selective reproduction of data on one card transposed from and under control of another card when the latter bears predetermined classification data.

It is obvious that reproduction of cards having certain classifications may be performed by manually sorting or machine sorting promiscuously arranged cards to sort out those having selected classifications and then reproducing them, but after such cards have been reproduced it is necessary to replace the selected cards back in the file, if the file is to remain intact.

This procedure is laborious and entails considerable handling of all cards in the file, with consequent possibility of misplacing cards.

It is, therefore, a broad object of the present invention to provide an improved means to select from a file of promiscuously arranged punched cards those having classification data corresponding to a setup in the machine and upon location thereof utilize such punched cards to transpose certain data thereon to another card.

A still further object of the invention is to enable the searching of selective classification data when it consists of all numerical data, all alphabetic data, or a mixture of both.

Another important feature of the invention is to provide for the selective reproduction of an alphabetically designated card dependent upon the location of searched-for zone classification data, and interrelated numeric data. This feature relates primarily to the search for alphabetic classification data where the latter is represented by combinations of zoning perforations at R, X, O and one in the same column at 9—1 index point positions.

Another specific object of the invention relates to the provision of improved means to suppress the feeding of blank cards until a punched card is found which corresponds to the selected classification data set up in the machine, and then under control of comparing means cause the concomitant feeding of a blank card past the punching mechanism as data to be transposed from the punched card is analyzed by supplemental analyzing means.

Another object of the invention relates to an improved means of construction of classification data setup means, consisting of an emitter which transmits data representing impulses. By convenient plug connections to the emitter selected impulses may be derived which correspond to the classification data searched for. Such emitter

also provides for the transmission of zoning impulses and numeric impulses which are selected in combination according to the searched-for letter of the alphabet.

5 Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a sectional view of the machine embodying the present improvements, showing the reading section of the machine at the left and

15 the reproducing punching section at the right.

Fig. 2 is a fragmentary sectional view showing the manner of placing the operation of the card feeding means for the reproducing control analyzing means under control of the reading clutch, 20 instead of the punch clutch as in Patent No. 2,032,805, corresponding Reissue Patent No. 21,133.

Fig. 3 is a plan view of the parts shown in Fig. 2 but inverted with respect to the latter.

25 Figs. 4a and 4b arranged in this order form the wiring diagram of the machine.

Fig. 5 is a diagrammatic view showing the manner of selective reproduction of blank cards under control of pattern cards which have selected 30 classifications.

Fig. 6 is a timing diagram.

In Fig. 1 there is shown a part of the essential elements of the card reproducing machine disclosed in Patent No. 2,032,805 or the corresponding Reissue Patent No. 21,133 and in briefly describing the operation of the mechanism and changes in the patented machine to carry out the present mode of operation, the same reference characters as far as is possible will be employed as are used in the patent to facilitate ready reference thereto for any further detailed explanation.

Referring to Fig. 1, in the magazine R are placed a series of promiscuously arranged punched pattern cards 10, from which file certain cards are to be reproduced.

Arm 57 is oscillated to cause the reciprocation of a slide 53, said slide carrying a picker 58 for advancing the lowermost card to a pair of feed 50 rollers 59, 60 which convey the card to a sensing or analyzing station comprising brushes 15 and contact roller 262, from which station the card passes to feed rollers 65, 66 and from there to a second sensing station comprising brushes 16 and contact roller 281 and here the card is conveyed 55

by rollers 88, 97 and eject roller 102 to a discharge hopper 12.

In the magazine P of the punching section of the machine cards 11 which are blank in the columns to be punched are placed which are to be selectively punched under control of the selected pattern cards in the magazine R. From the magazine P the cards are fed singly by means of an arm 83, slide 84 and picker knife 85 to feed the lowermost card to rollers 103, 104, which convey the card to and past the punching station comprising a row of punches 18 and a die 167. From the punching station the card is conveyed by rollers 105, 106, 131, 132 and eject roller 145 to a discharge hopper 13. The sets of rollers which convey the blank card through the punching section of a machine are intermittently driven as explained in the aforementioned Patent No. 2,032,805, so that the card is advanced in steps with each row of index point positions, causing momentarily a stop at the punching positions to receive the perforations if, at such time, the PM magnets are energized.

Energization of magnet PM will rock its armature structure 190, drawing a link 192 toward the right to effect coupling between an interposer 186 and plate 184. The plate 184 is carried by the member 177, pivoted at 183 and oscillated by means of a link 178 connected to an arm 176 on the shaft 175.

Further detailed explanation of the construction and operation of the card feed and punch mechanism may be had by reference to Patent No. 2,032,805 and it will be sufficient for the purposes of the present invention to now explain that when a card 10 previously found to contain perforations representing a classification set up in the machine passes brushes 16, circuits are completed through the perforations in the pattern card to energize the punch magnets PM, which magnets will couple the related punches to the oscillating plate 184 and effect punching in the corresponding index point positions of the blank card fed from the magazine P. After the pattern card and the blank card have concurrently passed their respective sensing and punching stations, the punched card is then fed by the rollers 105, 106, 131, 132, eject roller 145 to the hopper 13. The brushes 15 determine whether a pattern card represents the classification data set up in the machine as will appear clearer in the description of the machine involving the circuit diagram. However, before going to the description of the circuit diagram, certain mechanical changes are made in the present clutch drive and will now be described.

In the Patent No. 2,032,805 feeding rollers 65, 66, contact roller 281, feeding rollers 88, 97 and eject roller 102 are driven under control of the punch clutch engaged when the PCM clutch magnet is energized. In the present machine the operation of the aforementioned elements is removed from under control of the PCM clutch magnet and is placed under control of the RCM clutch magnets. The changes necessary to accomplish this are shown in Figs. 2 and 3.

In Fig. 2, reference numeral 37 designates a clutch driving gear 37 on shaft 38. The manner in which such gear is driven when the RCM clutch magnet is energized is fully described in Patent No. 2,032,805. When such clutch is engaged the card feeding mechanism associated with the R magazine (Fig. 1) is operated to feed a card and to also drive feeding rollers 59, 60 and contact roller 262 by gear connections fully

described in the aforementioned patent. The manner in which the remaining feeding rollers 65, 66, 88, 97, 102 and contact roller 281 of the reading section are operated will now be described, it being noted that the feeding rollers 59 and 60 are driven by a gear 61 (Fig. 2) secured to shaft 38. Gear 61 meshes with a gear 62 on the roller 59. A smaller gear 63 on roller 59 cooperates with a similar gear 64 on roller 10 so that both rollers are turned simultaneously but oppositely. Gear 63 on roller 59 meshes with an idler gear 67 which in turn meshes with a gear 68 on contact roller 262. From said gear 68, gear connections are now provided to drive the feeding rollers 65, 66, common contact roller 281, feed rollers 88, 97 and the eject roller 102.

The drive gear designated 92 in Patent No. 2,032,805 (see Fig. 2) has been removed and an idler gear designated 68a (Fig. 2) is provided herein and is pivoted on a stud so that it meshes with the contact roll drive gear 68. Said idler gear 68a also meshes with gear 93 attached to the feed roller 65. Gear 93 on the feed roller shaft 65 also meshes with a similar gear 94 on the feed roller shaft 66. So far described, it is obvious that feed rollers 65 and 66 are driven by the RCM clutch of the reading section.

Also herein as in Patent No. 2,032,805, gear 78, driven by the PCM clutch, meshes with gear 86 and the latter meshes with a gear 87 (see Figs. 2 and 3). However, in Patent No. 2,032,805, gear 87 is secured to an extension of the feed roller drive shaft 88, but herein gear 87 is secured to a short jack shaft 87a (Fig. 3), axially aligned with the feed roller drive shaft 88. In other words, feed roller drive shaft 88 does not now extend sufficiently to carry the gear 87 and also the gear 89 but is broken at the point indicated by the legend in Fig. 3 as "Shaft 88 cut here." However, on stud shaft 87a the gear 89 is attached which meshes with a gear 90 attached to a shaft 91 which carries the cams for operating the cam contacts P1—P6. Thus, the latter are driven when the PCM clutch is engaged, the same as in Patent No. 2,032,805. The severing of feed roller shaft 88 at the place indicated now disconnects the feeding of the rollers 65, 66, 88, 97, contact roller 281 and eject roller 102 by the PCM clutch and enables such elements to be driven by the RCM clutch magnet. To effect this, gear 93 which, it will be recalled, is driven when the RCM clutch is engaged, meshes with an idler gear 98 and the latter meshes with a gear 99 secured to the shaft of the contact roller 281. The gear 99 meshes with an extra idle gear 99a provided in the present machine and which meshes with gear 95, carried by the feed roller 88. Gear 95 on roller 88 drives a similar gear 96 on associated roller 97. Another idler gear 100 meshes with gear 95 and serves to drive pinion 101, mounted on card eject roller 102. Summarizing, such changes in the driving connections of the patented machine enables all of the feeding rollers and contact rollers of the reading unit shown at the left of Fig. 1 to be driven whenever the RCM clutch is engaged.

Operation of machine in connection with wiring diagram

Prior to starting the operation of the machine, punched pattern cards of the file from which cards having certain classifications are to be reproduced are inserted in the reading unit magazine R. Like the machine disclosed in Patent No. 2,032,805, the magazine of the reading unit is pro-

vided with a card lever shown in Figs. 1 and 4a and designated RMCL and closure of the related contacts will close a circuit from the line 200 through such contacts, R6 relay to line 201. Also prior to the operation of the machine blank cards are placed in the magazine of the punching unit and the related card lever PMCL (Figs. 1 and 4a) is operated to close its related contacts to energize the R3 relay by an obvious circuit.

Thus, prior to the depression of the start key ST, the R6a and R3a relay contacts (Fig. 4a) are transferred. Depression of the start key ST causes the first card in the reading unit magazine R to be fed just to the comparing brushes 15 while the first card in the punching unit feed magazine P is fed just to the punching die 161. The depression of the start key ST closes a circuit from the line 200, start key contacts, R6a contacts now transferred, R3a contacts now transferred, R10 relay coil to line 201. The latter closes its contacts R10a and the latter remain closed as long as the start key is maintained depressed. Under control of the R10a contacts a motor control circuit will be closed from the line 200, R10a relay contacts, HD#1 relay coil to line 201. The latter closes the HD#1a contacts, thereby connecting the supply line to the main drive motor M. Motor M now being operated drives all of the unclutched mechanism of the machine as well as the shaft which closes the C cam contacts.

Also upon closure of the R10a contacts, the R9 motor relay is energized by a circuit from line 200, R10a relay contacts now closed, R13b contacts now closed, R9 relay, to line 201. A holding circuit for the R9 motor relay extends back through the R9a relay contacts, R9b relay contacts, R10a relay contacts, to line 200. An alternative holding circuit extends through the R9a contacts, C3 cam contacts back to line 200. It will be observed that the R9a relay contacts cannot be picked up unless the R13b relay contacts are closed. Referring to Fig. 4b, C4 cam contacts are timed to close the energizing circuit for the R13 relay between 9.6 at the end of the cycle and to 11.5 at the beginning of the next cycle. The opening of the R13b contacts prevents a pickup circuit for the R9 relay during this time. The starting circuit for the R9 motor control relay is held through R9a relay contacts and cam contacts C3 after the start key is released.

With R9c relay contacts and R10b relay contacts now closed, the circuit for the PCM clutch magnet is closed from the line 200, relay contacts R9c, R10b, relay contacts R1a, normally closed, cam contacts C1, PCM clutch magnets to line 201. The clutch magnet will be energized when cam contacts C1 close at the end of the cycle and through the clutch connection thus made the picker 85 will feed the lowermost blank card out of the P magazine and just to the punches 18 and die 161 at the punching station. During this first card cycle the blank card operates the die card lever DCL (Figs. 1 and 4a) and closes related contacts to energize the R1 relay by an obvious circuit and thus transfer R1a and R1c contacts. A circuit to energize the RCM clutch magnets is closed from the line 200 through R9c relay contacts, R10b relay contacts, R4a contacts now normal, S1 switch, R14b contacts now normal, S2 switch, C2 cam contacts, RCM clutch magnets to line 201. Thus, the related clutch is now engaged so that picker 58 will feed the lowermost card from the R magazine to the comparing sensing brushes 15. During this feeding cycle the

card just fed operates card lever RCL#1 (Figs. 1 and 4a) to close the associated contacts and by an obvious circuit energizes the R4 relay to transfer the R4a, R4c contacts. The energization of relays R1 and R4 will then condition circuits so that subsequent cards may be automatically fed from the respective magazines but during the first card feeding cycle the following circuits occur to prevent the energization of the PCM clutch magnet during the following or second card feed cycle, initiated automatically as will be subsequently described.

It will also be noted that the energization of the R1 and R4 relays transfer their respective contacts R1a and R4a so that the energizing circuit for the PCM clutch magnets now extends from line 200 through R9c contacts now closed, R10b contacts now closed, R4a contacts now transferred to a wire 204, the remainder of this alternative energizing circuit for PCM clutch magnets extending through R97b contacts now open as will be presently explained, through C1 cam contacts, PCM magnets, to line 201. At this time of the cycle it should be observed that the transfer of the R1a contacts opens the previously described energizing circuit for PCM clutch magnets which is effective during the first card feed cycle. The opening of relay contacts R97b prevents the completion of the circuit when cam contacts C1 close just prior to the second cycle.

In Fig. 4b Em represents an emitter driven synchronously with the C cam contacts (and also R and P cam contacts) and therefore its brush may be operated by the same continuously driven shaft 40 of the patented machine, and Fig. 2 herein. Emitter Em is timed to transmit impulses synchronously with the feeding of the pattern card past the comparing brushes 15. It will be recalled that in this machine the perforations are sensed in the order R, X, O, 1-9 and correspondingly emitter Em is timed to transmit impulses in this order (see Fig. 6). Digit representing impulses may be selected by making plug connections from the plug hubs 205 of the emitter to plug hubs 206 connected to comparing relays R57, R59, R61 and R63. Assuming that cards are to be reproduced only when pattern cards are found punched to represent the classification number 3578, plug connections (not shown for this example) will be made from the four plug hubs 206 to the plug hubs 205 having the corresponding numeral designations. Therefore, during the first cycle of the machine initiated by depression of the start key, a circuit will be closed from line 200 through circuit breaker contacts C11 (Fig. 4b), S3 switch now closed, R1 cam contacts (driven by shaft 38) (Fig. 2) closed during the time that all of the digit impulses are transmitted by the Em emitter, through the R3b relay contacts now closed, (R1b contacts now being open), to the common conducting strip of the emitter Em, through the brush thereof, the related contact points, plug hubs 205, plug connections (not shown) to the plug hubs 206, to the R57, R59, R61, R63 relays to line 200. Hence, the 3, 5, 7 and 8 impulses successively energize the relays in the named order, energizing the pickup windings thereof. Each pickup coil when energized closes its "a" holding contacts, energizing the H holding winding of each by a circuit from line 201, through the respective holding winding, its related "a" holding contacts, wire 207 through the holding cam contacts C9 to line 200. It will be observed that the

energized relays are held energized until 9.6 of the cycle.

Each relay R57, R59, R61 and R63 transfers its respective "b" comparing contacts which are cross-connected with the "b" comparing contacts of comparing relays R58, R60, R62 and R64. It is explained at this time that the last mentioned group of relays are selectively energized under control of the perforations in the pattern card when sensed by the brushes 15. Since, during the first card cycle the card has not been fed sufficiently past the brushes 15 and card lever contacts, relays R58—R64 remain deenergized and therefore the "b" comparing contacts are in the position shown in Fig. 4b. When the emitter transmits the 3 digit representing impulse at 3.3 in the cycle, at this time cam contacts C10 close to transmit an impulse from the line 200 through such contacts, wire 208, thence through the R57b contacts now transferred, R58b contacts now normal and through a plug connection 209 to the pickup winding of the R97 relay to line 201. Each comparing order is also effective to energize the R97 relay by reason of the shunt connections 210 so that similar energizing circuits for the R59, R61, R63 relays may be effective at 5.3, 7.3 and 8.3 points in the cycle to repeatedly energize the R97 relay through the R59b, R61b and R63b contacts and the associated "b" contacts of the unenergized R60, R62 and R64 relays. However, the first impulse transmitted to the R97 relay is effective and the pickup winding thereof closes the related holding contacts R97a and a circuit is then closed from the line 201 through the holding winding of R97 relay, R97a contacts, R4 cam contacts and wire 211 to the line 200. It will be observed from the timing shown in Fig. 6 that the R4 cam contacts hold the R97 relay energized until the remainder of the cycle and during the first portion of the next cycle, during which time the C1 cam contacts close. With the R97b relay contacts (Fig. 4a) now open and held open during the time that the C1 cam contacts are closed, it will be seen that the alternative energizing circuit for PCM magnets from the wire 204 through the R97b relay contacts, C1 cam contacts to PCM clutch magnets is now opened at R97b and, therefore, the clutch of the punch unit is not engaged, and the first card fed from the P magazine remains in position just before the die 167, and such blank card will be fed only past the punches 18 whenever a pattern card is found to represent the selected classification data.

The second card feed cycle is initiated automatically, as will be obvious from the subsequent description of circuits which keep the R10 relay energized. The energizing circuit for energizing the RCM clutch magnets for the second card feed cycle extends from line 200 through R9c relay contacts now closed, R10b relay contacts now closed, R1a relay contacts now transferred, thence through the R14b relay contacts now closed, S2 switch, C2 cam contacts, RCM clutch magnets to line 201. Thus, the clutch of the reading unit is now engaged and the card which was fed just to the comparing brushes 15 is now fed past such brushes for the analyzing of the perforations representing the classification data on such card. If the classification data is found to agree with the setup on the emitter Em then both the clutches of the reading unit and the punching unit are engaged and the first blank card is fed past the punches and die in synchronism with the feeding of the punched card past

the reproducing control brushes 16. However, it is explained that after the manual initiation of the first card feed cycle, the machine will run automatically until cards in either magazine are exhausted or the stop key is depressed. This is accomplished by keeping the R10 relay energized by the following described circuits:

When the R10 relay is energized by the start key depression, a holding circuit therefor is provided through R10c contacts, R24a relay contacts, P6 cam contacts, back to line 200. Relay contacts R24a are closed by R24 relay energized under control of the R2 cam contacts. From Fig. 6 it will be observed that cam contacts R2 close to energize the R24 relay to close the R24a relay contacts just prior to the closure of the P6 cam contacts so that the hold circuit for R10 relay is closed when the P6 cam contacts close at 13.4 at the end of the cycle. The holding circuit remains closed for the end of this cycle and up to 9.4 of the next cycle when cam contacts R2 open. From 9.4 to 13.4 of this next cycle the holding circuit is open and if in the meantime a shunt circuit is closed, R10 relay remains energized to start the next machine cycle. This shunt circuit is a supplemental holding circuit for the R10 relay and extends through the R10d relay contacts, punch magazine card lever relay contacts R3d now transferred, die card lever relay contacts R1c now transferred, switch S1 now in the position shown, reading magazine card lever relay contacts R6b now transferred, RCL#1 card lever relay contacts R4c now transferred, stacker stop switches S6, S5, stop key contacts, back to line 200. If this shunt holding circuit is not completed between 9.4 to 13.4 of a cycle the start relay R10 will deenergize, the clutches R and P will latch up to disengaged position and the machine will coast to a stop between 6 and 9 under control of the C3 cam contacts. When cards are fed to operate RCL#1 and DCL, the above shunt circuit is closed between 7—8 before P6 and R24a contacts open at 9.5 and 9.4 respectively, to keep R10 relay energized to effect the next cycle of operation automatically.

When the machine operates automatically for the next cycle, cam contacts C2 will close at the beginning of the cycle to transmit an impulse to the RCM clutch magnets to then feed the next pattern card from the R magazine and concurrently feed the pattern card which was previously fed just to the analyzing brushes 15, past said analyzing brushes to search the perforated columns representing the classification data to determine whether it agrees with the emitter set up. According to the result of the comparing operation the machine may effect either of two operations; (1) when agreement is found the blank card fed just to the die 167 is fed past the card punches 18 concurrently with the feeding of the pattern card past the reproducing control brushes 16, or (2) when disagreement is found the feeding of a blank card is suppressed and the next pattern card is fed past brushes 15 to determine whether it represents the classification data searched for. It will be assumed that condition (1) occurs whereupon the following operation takes place.

Preparatory to feeding the pattern card to the analyzing brushes 15, RCL#2, card lever is operated to close the related contacts (see Figs. 1 and 4b). As the pattern card passes the comparing brushes 15 circuits are closed through the perforations to the comparing relays R58, R60,

R62, R64, one of such representative circuits being traced as follows: Line 200, circuit breaker contacts C11, switch S3, R1 cam contacts closed during the analysis of the card, RCL#2 card lever relay contacts, brushes 15, and related plug connection to the pickup winding of associated comparing relays R58, 60, 62, 64, to line 201. If the pattern card is perforated to represent 35, 78, impulses are transmitted to the aforesaid relays at differential times. Holding circuits for such relays are provided by the "a" contacts and cam contacts C9, as before. Also synchronously with the analysis of the pattern card emitter Em is transmitting impulses at the same differential times to the other comparing relays R57, 59, 61, 63 by the aforementioned circuits. Where there is an agreement in numerical value in each order, paired comparing relays R51, R58; R59, R60; R61, R62; R63, R64 are concurrently energized and the concurrent transfer of their related "b" comparing contacts prevents an impulse from being transmitted to R97 relay. The R97b contacts of the latter remain closed and when C1 contacts close, an impulse is transmitted to PCM clutch magnets, and when C2 cam contacts close an impulse is transmitted to RCM clutch magnets. The machine now operates for the next cycle to feed a blank card past the punches 18 concurrently with the analysis of card perforations in the pattern card as it passes the reproducing control brushes 16. Brushes 16 may be correlated with the same card columns representing the searched numerical classification to thereby transpose such values to the blank card, or other columns of data may be analyzed by brushes 16 and transposed to the blank card. In either instance the punch magnet operating circuits are under control of brushes 16 described as follows: Just prior to entering the reading station comprising brushes 16, CCL card lever operates to close its related contacts (see Figs. 1 and 4b). The circuit extends from line 200, through circuit breaker C11, P1 cam contacts closed during the analysis of the card perforations, CCL card lever contacts now closed, brushes 16, and respective plug connections to the PM punch magnets connected to line 201. Of course, following cards are fed from the magazines R and P, and the punched pattern card following the one analyzed by brushes 16 will be analyzed by brushes 15 to determine if it represents the searched-for numerical classification.

If condition 2 occurs then R97 relay is energized and contacts R97b open to prevent PCM clutch magnets from energizing. However, clutch magnets RCM energize to feed a following card past the brushes 15 to search for its numerical classification, and at the same time the card not having the desired numerical classification is fed past brushes 16. Since P1 contacts are not closed the analysis of the perforations by brushes 16 is ineffective and punch magnets PM are not energized. It is explained that due to the change in construction herein whereby feeding rollers 65, 66, contact roller 281, feeding rollers 88, 97, eject roller 102 is driven by the RCM clutch such undesired pattern card is fed to the hopper 12.

Thus the machine operates automatically until either one or the other of the magazines R, P is empty, whereupon the machine will stop. Circuits for effecting this are well known and briefly when the P magazine is empty, R3d contacts transfer to normal to break the holding circuit for the R10 relay. The punch unit cannot be 70

restarted unless the P magazine is refilled because the start circuit to energize R10 relay by depressing the start key will be open at normally open R3a relay contacts.

5 When the reproducer magazine R becomes empty the machine will stop because R6b contacts transfer to normal to deenergize the R10 relay. However, the machine may be restarted for one cycle by depressing the start key although the R magazine is not replenished. In this case RCL#1 contacts are closed to energize R4 relay and R4d contacts are transferred. The start circuit is now from the start key ST, R6a normally closed contacts, R4d contacts now transferred, R3a contacts now transferred, to R10 relay. During this card feed cycle the last card on the reading side will advance past brushes 15 to brushes 16. Since the card leaves RCL#1 card lever contacts R4c are now open to break the holding circuit of the R10 relay, and the machine will now stop. Also R4d contacts come to normal. The start circuit is now closed upon depression of the ST key, the circuit extending through the normally closed contacts R6a, R4d, R3a to the R10 relay. The previous analysis of the pattern card by brushes 15 will determine whether such agrees with the numerical setup and if found to agree will cause the last blank card to be fed past the card punching mechanism 20 in synchronism with the feeding of the last pattern card past the brushes 16. If agreement is found the circuit to energize the PCM clutch magnets is from line 200, R9c relay contacts, R10b relay contacts, R4a relay contacts normally closed, R1c relay contacts now closed, R3c relay contacts, wire 204, R97b relay contacts, C1 cam contacts, PCM clutch magnets, to line 201.

If both feed magazines become empty at the same time, the machine will stop and it will be necessary to insert in the P magazine one blank card, if the machine is to be cleared of cards; otherwise both magazines are replenished with cards.

45 *Selective card punching determined by pattern cards having alphabetical classification data with or without numerical classification data*

Another feature of the machine consists in providing for selective card punching when the 50 classification data on pattern cards represents alphabetical data with or without numerical classification data. For example, pattern cards representing AB89, taken in the following as an example, can be selected from classifications such as ABAB, 1212, DZHK, DB12, etc.

55 The alphabetical code may be any suitable one, and preferably consists of the code used to represent alphabetical data by the Hollerith type of card bearing twelve index point positions 9-1, O, X and R, such code being identified in Patent No. 2,315,741. In such code A is represented by a combination of holes at R and 1, and B by holes at R and 2.

60 When comparing data represented by two successively analyzed holes in a card column the Em emitter is plugged to emit such impulses to a single comparing relay R57, 59, 61, 63. To prevent possible back circuits when searching for combinational holes in a column a selector relay 101 and associated contacts a, b, are used for each column that combinational holes are searched for. Relay 101 is energized by an obvious circuit under control of the R5 cam contacts which closes during the analysis of the zoning holes R, X, O (see Fig. 6) and closes its "a"

multiple contacts. During the analysis of the numeric holes 1-9 in the named order, the "b" contacts are at normal and closed. Since search is made in the above example for the zone hole R in two card columns, plug connections 212, 213 are made from R impulse plug socket 205 to R, X, O plug sockets of the selector. Also since a search is made for digit impulses 1 and 2, plug connections 214, 215 are made from digit representing plug hubs 205 of the emitter to the 1-9 plug sockets of the selector. The plug connections 216, 217 are made to the respective R57, R59 comparing relays. Plug connections 218, 219 are made between the 8 and 9 plug hubs 205 to plug hubs 206 of the R61, R63 relays, in order to search for the 8, 9 numerical data.

While brushes 15 are searching the two left hand card columns for R, X, O perforations, cam contacts R5 are closed to close the "a" contacts of the selector and upon presence of such R perforation in the assumed example impulses are transmitted to the R58, R60 comparing relays. Concurrently, the Em emitter transmits an impulse when R point is contacted, the impulse being directed through the "a" closed contacts to the paired relays R57, R59. The holding circuits for the comparing relays extends through related "a" contacts and cam contacts C8 closed during R, X, O time. (See Fig. 6.) Thus, if there is an agreement in the zoning perforations, R97 relay remains unenergized. Thereafter, the Em emitter transmits through the "b" contacts of the selector 1 and 2 digit impulses to the R57, R59, relays at the time paired relays R58, R60 are energized by the same impulses under control of brushes 15. If there is an agreement in numeric data R97 relay still remains unenergized. Of course, non-simultaneous impulses, either zoning or numeric, cause one or the other of the paired relays to be energized, and through the comparing circuit cause R97 relay to be energized.

Summarizing, selective punching is dependent upon agreement in the two zones, since dissimilarity in either zone causes R97 relay to be energized and selective punching suppressed.

The above example merely takes two alphabetic characters A, B, as an example, and for other characters X, O, index points may be the searched-for zoning holes and plug connections are made from corresponding plug hubs 205. All the compared columns may consist of alphabetic data, the 101 selector relay having the desired number of contacts to prevent back circuits. Such back circuits may be explained by stating that without a selector and direct plug connections from Em to the comparing relays, the 1 digit impulse transmitted by Em would be directed to R57, back to R plug hub 205, and from such plug hub to R59 relay, improperly energizing the latter.

The size and number of data groups that are utilized are dependent upon the number of comparing relays. If another data group is used for control, similar comparing relays and comparing network are provided to selectively energize R98 relay, and since its "b" contacts (Fig. 4a) have a similar control, selective reproduction may be dependent upon finding another searched-for classification. Plug connections may be made as shown so that R97b and R98b contacts are in shunt so that agreement of only one data group will effect selective card punching and disagreement of both data groups prevents card punching. Obviously, changing plug connections to place contacts R97b and R98b in series will en-

able selective card reproduction only when both classification data groups agree with the respective numerical setup, and disagreement of only one group of classification data prevents card reproduction.

Each data group may consist of all alphabetic data, all numeric data, or intermixed. All of the above variations follow from the present disclosure and show the wide variety of uses of the present machine.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a record reproducing machine controlled by pattern records containing data to be reproduced, and alphabetical and interrelated numerical classification data, manually setup means set up to effect a representation of said numerical classification data and said alphabetical classification data, which alphabetical setups are made manually in combination according to a code to represent searched-for letters, means for sensing the numerical classification data perforations and alphabetical classification data perforations in alphabetically and numerically designated columns of said pattern record, comparing means controlled by said sensing means and setup means for determining agreement or disagreement between said alphabetical setup and alphabetic data representing perforations and numerical setup and numerical data representing perforations, and reproducing punching means controlled by said comparing means to effect upon detecting agreement in all classification data reproduction of data on said pattern record to another record.
2. In a record reproducing machine controlled by pattern records containing data to be reproduced and alphabetical classification data, setup means set up to effect a representation of said alphabetical classification data searched for including, for each letter of the alphabet, a zone representation setup and a numeric representation setup, means for sensing the zone and numerical classification data perforations of said pattern record wherein perforations are arranged in combination to designate a letter, reproducing punching means for reproducing data on said pattern record on other record material, comparing means controlled by said sensing means and setup means for determining in one comparing operation agreement or disagreement between said zone setup and zone representing perforations and in another comparing operation between each numeric perforation and the numerical setup, and means controlled by said comparing means to cause upon detecting an agreement in both comparing operations the operation of said reproducing punching means, and to prevent the operation of said reproducing means upon detecting in either or both comparing operations a disagreement.
3. In a record reproducing machine controlled by pattern records containing data to be reproduced and alphabetical classification data, setup means set up to effect a representation of said alphabetical classification data searched for in-

cluding, for each letter of the alphabet, a zone representation setup and a numeric representation setup, means for sensing the zone and numerical classification data perforations of said pattern record wherein perforations are arranged in combination to designate a letter, comparing means controlled by said sensing means and setup means for determining in one comparing operation agreement or disagreement between said zone setup and zone representing perforations, and in another comparing operation between each numeric perforation and the numerical setup, and punching reproducing means controlled by said comparing means to effect upon detecting an agreement in both comparing operations reproduction of data on said pattern record to another record.

4. In a record reproducing machine controlled by pattern records containing data to be reproduced and alphabetical classification data, setup means set up to effect a representation of said alphabetical classification data searched for including, for each letter of the alphabet, a zone representation setup and a numeric representation setup, means for sensing the zone and numerical classification data perforations of said pattern record wherein perforations are arranged in combination to designate a letter, reproducing punching means for reproducing data on said pattern record on other record material comparing means controlled by said sensing means and setup means for determining in one comparing operation agreement or disagreement between said zone setup and zone representing perforations and in another comparing operation between each numeric perforation and the numerical setup, and means controlled by said comparing means to cause upon detecting an agreement in both comparing operations the operation of said reproducing punching means.

5. In a record reproducing machine controlled by pattern records containing data to be reproduced and alphabetical and numerical classification data, setup means set up to effect a representation of said numerical classification data, and alphabetical classification data searched for including, for each letter of the alphabet, a setup of a zone representation and a numeric representation, means for sensing the numeric classification data representing perforations in certain columns and zone and numerical classification data perforations in other alphabetically designated record columns of said pattern record wherein perforations are arranged in combination to designate a letter, comparing means controlled by said sensing means and setup means for determining in one comparing operation agreement or disagreement between said zone setup and zone representing perforations, and in another comparing operation between each numeric perforation for alphabetic and numeric designated columns and the compared numerical setup, and reproducing punching means controlled by said comparing means to effect upon detecting a complete agreement in both comparing operations reproduction of data on said pattern record to another record.

6. In a record reproducing machine controlled by pattern records containing data to be reproduced and alphabetical and numerical classification data, setup means set up to effect a representation of numerical classification data and alphabetical classification data searched for including, for each letter of the alphabet a zone representation setup and a numeric representa-

tion setup, means for sensing the numeric classification data representing perforations in certain columns and zone and numerical classification data perforations in other alphabetically designated record columns of said pattern record wherein perforations are arranged in combination to designate a letter, reproducing punching means for reproducing data on said pattern record to other record material, comparing means controlled by said sensing means and setup means for determining in one comparing operation agreement or disagreement between said zone setup and zone representing perforations and in another comparing operation between each numeric perforation for alphabetic and numeric designated columns and the compared numerical setup, and means controlled by said comparing means to effect upon detecting a complete agreement in both comparing operations the operation of said reproducing punching means, and to prevent the operation thereof upon detecting a disagreement in either or both comparing operations.

7. In a cyclically operable record reproducing machine comprising pattern record sensing means for sensing zone perforations and numeric perforations combinationally arranged in a column to represent a letter, an emitter for transmitting concurrently with the sensing of said zone perforations differentially timed zone impulses, and concurrently with the sensing of said numeric perforations differentially timed numeric impulses, means for selecting a zone and numeric impulse representing a searched-for letter, relay comparing means controlled by said emitter and sensing means operable in one comparing operation to determine agreement or disagreement between a selected zone impulse and the zone perforation sensed, and in another comparing operation to determine agreement or disagreement between a selected numeric impulse and the numeric perforation sensed, reproducing punching means to effect the reproduction of data on said pattern record to other record material, and means controlled by said comparing means to cause the operation of said reproducing punching means upon agreement being found in both comparing operations.

8. In a selective record reproducing machine, setup means to effect a setup of a zone representation and a setup of a numeric designation of a searched-for letter, reproducing punching means for reproducing data on a pattern record to other record material, sensing means for sensing zone and numeric perforations of said pattern record, and dual comparing means controlled by said setup means and sensing means to prevent the operation of said reproducing punching means when disagreement is determined between the compared zone representation and zone perforation and/or between the compared numeric representation and numeric perforation.

9. In a record reproducing machine, sensing means for sensing a record perforated to represent alphabetic data by a combination of intra-zone numeric perforations and extra-zone perforations, setup means set up to represent a numeric designation and a zone designation corresponding to the combinational designations of a searched-for letter, and comparing means controlled by the aforesaid sensing means and setup means including means to render said comparing means effective to determine in one comparing operation agreement or disagreement in the setup of zone designations and zone perforations

and in a successive comparing operation agreement or disagreement in numeric perforations and the setup of numeric designations.

10. In a record punching machine of the class described, means to effect a setup of a zone representation and a numeric representation of a searched-for letter, means for sensing zone perforations and numeric perforations of a pattern record, comparing means to compare a zone setup with a zone perforation and to compare a numeric setup with a numeric perforation, and switching means for placing the comparing means under control of the sensing means and zone setup means for one comparing operation, and then placing said comparing means under control of said sensing means and said numeric setup means for another comparing operation.

11. In a record reproducing machine, means for sensing horizontal columns of a record in succession with like index point positions in a record analyzed concurrently for determination of zone perforations in the order R, X, O and digit perforations in the order 1-9, an emitter for transmitting differentially timed impulses in the order R, X, O, 1-9 synchronously with sensing the horizontal columns of the pattern record, means for selecting R, X, O impulses and a digit

impulse representative of the letter searched for, and relay comparing means controlled by said sensing means and emitter for determining an agreement or disagreement between the selected R, X, O impulse and selected digit impulse and the compared perforations sensed.

12. A cyclically operable machine comprising pattern record sensing means for sensing zone perforations and numeric perforations combinationally arranged in a column to represent a letter, an emitter for transmitting concurrently with the sensing of said zone perforations differentially timed zone impulses, and concurrently with the sensing of said numeric perforations differentially timed numeric impulses, means for selecting a zone and numeric impulse representing a searched-for letter, and relay comparing means controlled by said emitter and sensing means operable in one comparing operation to determine agreement or disagreement between a selected zone impulse and the zone perforation sensed, and in another comparing operation to determine agreement or disagreement between a selected numeric impulse and the numeric perforation sensed.
